AUXILIARY BLADE ATTACHMENT FOR BULLDOZERS

August Elmer Anderson, Isle, Minn.

Application November 23, 1953, Serial No. 393,562

2 Claims. (Cl. 37—143)

This invention relates to a bulldozer attachment and more specifically provides a device for detachable attachment to a conventional bulldozer blade wherein an auxiliary blade is provided in forwardly spaced relation to the ordinary bulldozer blade thereby making the conventional bulldozer more versatile, wherein the auxiliary blade may be utilized in back-filling ditches, grading wet spots and other operations which cannot be easily carried out by the conventional bulldozer.

A primary object of this invention is to provide a bulldozer attachment for attachment to a bulldozer blade having a concave blade normally facing the bulldozer blade for back-filling or the like.

Another object of this invention is to provide a bulldozer attachment having an adjustable concave blade spaced forwardly of the conventional bulldozer blade wherein the auxiliary blade may be used for pushing or pulling material.

A further object of this invention is to provide a bulldozer attachment which may be adjusted in angular relation to the conventional bulldozer blade and which may be adjusted in longitudinal relation to the conventional bulldozer blade.

Yet another object of this invention is to provide a bulldozer attachment which may be utilized for attachment to the conventional bulldozer blade or may be utilized in place of the conventional bulldozer blade on either crawler type or rubber type vehicles having hydraulic, electric or cable operated mechanism.

A still further object of this invention is to provide a bulldozer attachment which is universal in adaptability, versatile in use, simple and rugged in construction, and easily assembled and disassembled to its operating position.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of the bulldozer attachment of this invention secured to a conventional bulldozer blade and projecting forwardly therefrom;

Figure 2 is a side elevational view of the structure of Figure 1;

Figure 3 is a top plan view of the construction of Figure 1;

Figure 4 is a side elevational view of a modified form of bulldozer attachment; and

Figure 5 is a detailed side elevation showing another modified form of the bulldozer attachment.

Referring now specifically to the drawings, it will be seen that the numeral 10 generally designates the bulldozer attachment of this invention for attachment to a conventional bulldozer blade 12 having the usual mounting members 14 attached to the bulldozer (not shown). The attachment 10 may be attached to any type bulldozer

2

having any type operating mechanism for the bulldozer blade 12.

Referring now specifically to Figures 1-3, it will be seen that the attachment 10 includes an elongated plate 16 having an inwardly and upwardly inturned lower edge 18 which fits under and around the bottom of the bulldozer blade 12. The upper end of the plate 16 is provided with a horizontal portion 20 and a downwardly extending portion 22 which engages the rear of the upper edge of the bulldozer blade 12. A clamp bolt 24 is positioned between the depending portion 22 and the plate 16 thereby urging the depending portion 22 against the rear surface of the blade 12 thereby securely clamping the plate 16 to the bulldozer blade 12. A pair of vertically aligned and vertically spaced pivot lugs 26 are disposed on the plate 16 at each remote edge thereof and each of the lugs 26 pivotally supports a longitudinally extending support member 28 in the nature of a tubular pipe. Each of the tubular support members 28 slidably receives a second support member 30 in telescopic relation. The outer end of the tubular member 28 is provided with a plurality of holes 32 and the member 30 is maintained in adjusted position by a transverse pin 34 which functions in an obvious manner. The outer ends of the support members 30 are secured to a concave blade 36 pivotally mounted on the lower of the support members 30 on an axis 38 which is located at substantially the center of the blade 36. The remote ends of the upper support members 30 are attached to suitable lugs 40 on the convex surface of the blade 36. A brace member 42 extends between the lower support member 30 and the lug 40 for retaining the support members 30 in rigid relationship. A pair of cross-braces 44 are pivotally attached on lugs 46 located on the inner surface of the tubular members 28 adjacent the plate 16 and are slidably attached to lugs 48 having elongated slots 50 therein adjacent the outer end of the support members 30 wherein the support members 30 and 28 may be telescopically adjusted and the cross-braces 44 retain the members 28 and 30 in correct and rigid relationship. A lug 52 similar to the lug 40 is secured to each end of the plate 36 at the bottom thereof and by disconnecting the bolts 54 and a bolt 56 holding an adjustable brace 58 to the concave portion of the blade 36, the blade 36 may be pivoted about the axis 38 wherein the concave portion of the blade 36 is facing forwardly or in the same direction as the concave surface of the bulldozer blade 12. The brace 58 includes a pair of strap members having a plurality of longitudinally spaced apertures 60 for longitudinal adjustment of the brace 58. The brace 58 is pivotally attached to a lug 62 on the under-surface of the support member 30 and a lug 64 on the concave surface of the blade 36 adjacent the lower edge thereof. When the blade 36 is pivoted about its axis 38 so that the concave portion faces forwardly, the brace 58 is attached to the lug 40 and it will be seen that it will be necessary to extend the brace 58 substantially as shown in phantom in Figure 4.

Referring now specifically to Figure 4, it will be seen that the bulldozer blade 12 includes a rearwardly extending flange 13 on its upper edge. A clamping member 66 includes a pair of spaced hook members 68 and 70 for selective engagement with the flange 13 and a clamp bolt 72 is provided for urging the respective hooks 68 and 70 into engagement with the flange 13. In the specific embodiment as illustrated in Figure 4, the hook member 68 engages the flange 13 for securing the plate 16 to the blade 12. However, in some installations, it may be necessary to utilize the hook 70 to engage the flange 13, and in the specific embodiment as shown, the hook portion 70 engages the rear surface of the blade 12, thereby stabilizing the assembly. Pivotally attached to each of the upper of the lugs 26 is a strap member

74 having a plurality of longitudinally spaced apertures 76 for adjustably mounting a vertical portion 78 of a modified frame member 80. The modified frame 80 includes a pair of longitudinally extending support members 82 which includes vertically spaced rod members braced in rigid relation by suitable vertical braces 84 and angular braces 86. Upper braces 88 connect the upper portion of the support member to the vertical member 78. The outer ends of the support members 82 are attached to the blade 36 in the same manner as employed in Figure 1.

In the device as shown in Figure 5, the frame 90 is modified and the upper and lower support members 92 are secured together with the usual bracing 84 and 86 and a hydraulic piston and cylinder arrangement 94 is pivotally disposed between the upper of the lugs 26 and the inner end of the upper support member of the frame 92. The plate 16 in this modification is held on the rearwardly extending flange 13 by a hook-shaped solid member 96 held thereon by a clamp bolt similar to 72.

The operation of the device will be readily understood. The plate 16 is attached to the bulldozer blade 12 in an obvious manner and with the blade 36 positioned with the concave surface thereof facing the bulldozer blade, the attachment 10 may be used for back-filling ditches, back-grading wet spots and smooth back-grading. With the blade 36 having a concave surface facing forwardly, the device is utilized as an extension of the bulldozer blade 12 and may be efficiently utilized in places where the bulldozer cannot have access. In the specific embodiments as shown in Figures 4 and 5, the attachment may be adjusted in angular relation to the bulldozer blade thereby making the attachment more versatile and useful. The attachment of this invention greatly increases the versatility of a bulldozer and makes the bulldozer usable for many jobs for which it was previously unsuited to perform. Obviously, any well known materials may be utilized in the construction of this device, and it will be understood that the various braces and supporting members may be constructed of such a size to meet the requirements of this particular device.

From the foregoing, the construction and operation

of the device will be readily understood and further explanation is believed to be unnecessary. However, since numerous modifications and changes will readily occur to those skilled in the art, it is not desired to limit the invention to the exact construction shown and described, and accordingly, all suitable modifications and equivalents may be resorted to, falling within the scope of the appended claims.

What is claimed as new is as follows:

- 10 1. A bulldozer attachment comprising a plate, clamp means associated with said plate for attaching said plate to a bulldozer blade, an elongated frame pivotally connected to and projecting forwardly of said plate, means for adjusting said frame about said pivotal connection with said plate, a concave blade pivotally mounted on the outer end of said frame, said concave blade having the concave portion normally facing said plate, said frame including upper and lower spaced longitudinally telescoping support members.
- 15 2. A bulldozer attachment comprising a plate, clamp means associated with said plate for attaching said plate to a bulldozer blade, an elongated frame pivotally connected to and projecting forwardly of said plate, means for adjusting said frame about said pivotal connection with said plate, a concave blade pivotally mounted on the outer end of said frame, said concave blade having the concave portion normally facing said plate, said frame including upper and lower spaced longitudinally telescoping support members, slotted lugs attached to said support members, and cross braces extending between said support members engageable in said slotted lugs.
- 20 25 30
